A. WESCHKE

GYMNASTIC IMPLEMENT

Filed March 17, 1926

Inventor:

Alexander Weschke

by *Neuhard*
Atty.

Patented June 7, 1927.

UNITED STATES PATENT OFFICE.

ALEXANDER WESCHKE, OF BERLIN-SCHONEBERG, GERMANY.

GYMNAStic IMPLEMENT.

Application filed March 17, 1926, Serial No. 95,451, and in Germany November 18, 1924.

My invention relates to gymnastic implements and more particularly to a training device comprising a handle and a mass or weight resiliently connected to said handle by a rod, spring or the like. It is an object of my invention, among others, to provide a device of the kind described allowing to vary the vibrations or oscillations imparted to the weight by swinging the device.

5 To this end I divide the usual rod connecting the handle with the weight into two parts and I connect these parts by a coil spring.

In the drawings affixed to this specification and forming part thereof a device embodying my invention is illustrated diagrammatically by way of example.

Referring now to the drawings, *h* and *h'* are rods or tubes which are connected by a coil spring *f*. On the rod *h*, which may be 20 of metal tubing, there is secured a handle *c* by a countersunk setscrew *i* so that the position of the handle *c* on the rod *h* may be varied. The other part *h'* carries a weight 25 *b*. The two parts *h* and *h'* are connected by a coil spring *f* which is preferably secured on the threaded adjoining ends *g* and *g'* of the parts *h* and *h'* respectively. The weight 30 *b* is held on the part *h'* in any desired position by a setscrew *d* and a disc *e* which is screwed into the end of the part *h'*. The disc *e* and the setscrew *d* cooperate to hold

the weight *b* against leaving the part *h'*. The amplitude and the frequency of the oscillations of the device can be varied by exchanging the spring *f* for a spring of other, greater or smaller, resilience, but obviously a variation may also be obtained by exchanging the weight *b* or by displacing the handle *c* after unscrewing its setscrew *i*. The 40 spring *f* is readily exchanged by turning the threaded ends *g* and *g'* of the parts *h* and *h'* out of it.

I wish it to be understood that I do not desire to be limited to the exact details of 45 construction shown and described, for obvious modifications will occur to a person skilled in the art.

I claim:

1. Gymnastic device comprising a handle 50 and a weight, separate rods secured to said handle, and to said weight, and a resilient connection between said rods.

2. Gymnastic device comprising a handle and a weight, separate rods secured to said 55 handle, and to said weight, and a coil spring connecting said rods.

3. Gymnastic device comprising a handle and a weight, separate rods secured to said handle, and to said weight, and an exchangeable coil spring connecting said rods. 60

In testimony whereof I affix my signature.

ALEXANDER WESCHKE.
